WILLIAM A. SMITH, JR., OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed February 15, 1929. Serial No. 340,262.

This invention relates to fluid actuated rock drills, but more particularly to a valve for effecting the distribution of pressure fluid to the ends of the cylinder.

5 One object of the invention is to obtain a light weight valve which is positive and quick in its action, and another object is to throw the valve at the most advantageous point in the cycle of operations so that the drill may 10 be actuated with a minimum consumption of pressure fluid.

Other objects will be in part obvious and in part pointed out hereinafter.

In the drawing illustrating a practical application of the invention and in which similar reference characters refer to similar parts,

Figure 1 is a sectional elevation of a rock drill equipped with a valve constructed in accordance with the practice of the invention and showing the valve in one of its limiting positions, and

Figure 2 is a view similar to Figure 1 showing the valve in another limiting position.

Referring to the drawings, A represents a 25 cylinder having a piston chamber B in which is disposed a reciprocating hammer piston C. The cylinder A has a free exhaust port D which is controlled by the piston C.

A closure is provided for the front end of 30 the piston chamber B in the form of a front cylinder washer E having in this instance a bore F to receive slidably an anvil block G. The anvil block has a stem H projecting into the front end of the piston chamber B to receive 35 the blows of the hammer piston C. The function of the anvil block G is to transmit the blows of the hammer piston to a working implement designated by J and extending through a front head K seated against the front cylinder washer E whereby the cylinder A and the front head K are centralized 40 with respect to each other.

In the rearward end of the cylinder A is an enlarged bore L in which is disposed valve 45 mechanism designated generally by O, and into the extreme rearward end of the bore L extends a projection P of a back head Q which serves as a closure for the rearward end of the cylinder.

50 Among other functions the back head Q

serves as a housing for a throttle valve R whereby the admission of pressure fluid into the drill is controlled. Preferably the throttle valve R is of the rotary type having a lever S whereby it may be manipulated. 55

The pressure fluid for actuating the drill may be conveyed thereto through a suitable connection (not shown) and such pressure fluid may be introduced into a central chamber T of the throttle valve R. In the side of the throttle valve R is a port U adapted to register with a passage V in the back head leading in this instance to a supply reservoir W also in the back head. 60

The valve mechanism constructed in accordance with the practice of the invention comprises an intermediate plate X bearing with its front end against a back cylinder washer Y which serves as a closure for the rearward end of the piston chamber B and with its rearward end against a plate Z which acts as a seat for the back head Q. 65

The parts comprising the casing of the drill, such as the cylinder A, the front and back heads K and Q respectively, may be held 70 suitably clamped together by means of the usual spring pressed side rods (not shown). When thus secured together, the back head will be pressed firmly against the plates comprising the valve chest and will thus also 75 serve to hold these elements firmly in the operative position.

Formed in the plates X and Z, and in this instance also in the back head Q, is a valve chamber b comprising an enlarged portion c and a reduced portion d. The reduced portion d may as shown be formed in the plate Z and in the back head Q and the enlarged portion c is formed in the plate X. The pressure fluid for actuating the piston C is admitted 80 into the enlarged portion c of the valve chamber intermediate its ends and is conveyed thereto by a supply passage e leading from the supply reservoir W. 85

Pressure fluid passes from the valve chamber b to the front end of the piston chamber B through an inlet passage f and to the rearward end of the piston chamber B through a rearward inlet passage g. Preferably the inlet passage f opens into the valve chamber 90 95 100

5 *b* at a point near the rearward end of the enlarged portion *c* of said valve chamber and the inlet passage *g* opens into the same portion of the valve chamber at a point near the front end thereof.

10 The distribution of pressure fluid to the ends of the piston chamber is controlled by a valve designated by *h*. The valve *h* is of the spool type having a body portion *j* and a pair of flanges *k* and *o*. The flange *o* is formed at the foremost end of the valve *h*, and the flange *k* at a point intermediate the ends of the valve. Both flanges *k* and *o* are of the same diameter and lie within the enlarged 15 portion *c* of the valve chamber. The flanges *k* and *o* are so disposed with respect to the outlet opening of the supply passage *e* that pressure fluid will constantly be admitted into the valve chamber *b* in the space between the 20 said flanges *k* and *o*.

25 The rearward end of the body portion *j* extends into the reduced portion *d* of the valve chamber *b* and serves as an actuating surface *p* against which pressure fluid constantly acts tending to throw the valve *h* forwardly. The 30 pressure fluid utilized for this purpose is conveyed into the reduced portion *d* through a port or passage *g* leading from the supply reservoir *W*.

35 The front end of the flange *o* serves as an actuating surface *r* against which pressure fluid acts for throwing the valve *h* rearwardly. The pressure fluid utilized for this purpose is conveyed into the front end of the 40 valve chamber *b* by a leak passage *s* in the flange *o* which is in constant communication with the supply of pressure fluid in the space between the flanges *k* and *o*.

45 From the front end of the valve chamber *b* to a point in the piston chamber *B* forwardly of the exhaust port *D* leads a tripper passage *t*. The tripper passage *t* is in constant communication with the leak passage *s* so that pressure fluid will be constantly flowing into 50 said tripper passage *t* and when such pressure fluid is entrapped in the tripper passage by the piston *C*, it will act against the actuating surface *r* for throwing the valve rearwardly.

55 The outlet opening *u* of the tripper passage *t* may be conveniently located to obtain an early or late movement of the valve *h*, that is, if the outlet opening *u* be located near the front end of the piston, it will be covered by 60 the piston at a later period in the stroke of said piston and consequently the rearward movement of the valve *h* will be somewhat delayed. Conversely if the tripper passage *t* opens into the piston chamber *B* at a point 65 near the exhaust port *D*, it will be covered earlier by the piston *C* and the pressure fluid entrapped therein will therefore retract the valve *h* at an earlier period during the forward stroke of the piston.

70 65 The operation of the device is as follows:

With the valve *h* in the position illustrated in Figure 1, pressure fluid flowing from the supply reservoir *W* into the valve chamber will flow over the rearward surface of the flange *o* through the inlet passage *g* into the rearward end of the piston chamber *B* to drive the piston *C* forwardly against the anvil block *G*. At the same time pressure fluid will be flowing through the leak passage *s* into the front end of the valve chamber *b*, thence through the tripper passage *t* into the front end of the piston chamber *B* from whence it may flow to the atmosphere through the exhaust port *D*.

75 The pressure fluid flowing into the tripper passage *t* will follow these channels until the exhaust port *D* is covered by the piston *C*. When the piston *C* covers the outlet opening *u* of the tripper passage *t* and entraps the pressure fluid in the tripper passage, such 80 pressure fluid will act against the actuating surface *r* and when it becomes of sufficient value to overcome the pressure acting against the actuating surface *p*, the valve *h* will be thrown rearwardly to the position illustrated 85 in Figure 2.

90 In the new position of the valve, pressure fluid will flow over the forward surface of the flange *k* into the inlet passage *f* and the front end of the piston chamber *B* for actuating the piston *C* rearwardly. The valve *h* will remain in the retracted position until the piston *C* uncovers the exhaust port *D* on the rearward stroke of the piston. When this 95 takes place, the pressure fluid in the front end of the valve chamber *b* will escape to the atmosphere through the exhaust port *D* and the pressure fluid acting against the actuating surface *p* will again throw the valve *h* to its initial position.

100 105 I claim:

110 115 1. In a fluid actuated rock drill, the combination of a cylinder and a piston, an exhaust port in the cylinder, a valve chamber, inlet passages leading from the valve chamber to the cylinder, a valve in the valve chamber having a pair of flanges to control the inlet passages, an actuating surface on the valve constantly exposed to pressure fluid 120 tending to throw the valve in one direction, a second actuating surface on the valve of greater area than the first said actuating surface, a tripper passage leading from the valve chamber to the cylinder and controlled by the piston, and a leak passage constantly admitting pressure fluid into the tripper passage wherein such pressure fluid is entrapped by the piston to act against the actuating surface of greater area for throwing the valve in the other direction.

125 130 2. In a fluid actuated rock drill, the combination of a cylinder and a piston, an exhaust port in the cylinder controlled by the piston, a valve chamber, inlet passages leading from the valve chamber to the cylinder, a

valve in the valve chamber having a pair of flanges of the same diameter to control the inlet passages, an actuating surface on one end of the valve constantly exposed to pressure fluid for throwing the valve in one direction, a second actuating surface at the other end of the valve and of larger diameter than the first said actuating surface, a tripper passage leading from the valve chamber to the cylinder and controlled by the piston, and a leak passage in one flange constantly admitting pressure fluid into the tripper passage wherein such pressure fluid is entrapped by the piston to act against the actuating surface of greater area for throwing the valve in the other direction.

In testimony whereof I have signed this specification.

WILLIAM A. SMITH, JR.
